UNITED STATES PATENT OFFICE.

CARL OSCAR SWANSON, OF MOLINE, ILLINOIS.

CLOTHESLINE REEL.

Application filed April 15, 1925. Serial No. 23,264.

This invention relates to improvements in clothes line reels and its object is to provide a simple practical device of this type that is cheap to manufacture, durable, and efficient in operation.

With the foregoing and other objects in view the invention consists in the combination and arrangement of parts to be herein-after fully described, pointed out in the appended claim and illustrated in the accompanying drawing which forms a part of this application and in which—

Fig. 1 is a perspective view of the reel with the clothes line wound thereupon.

Fig. 2 is a view of the reel in elevation.

Fig. 3 is an edge view of Fig. 1.

Like reference characters denote corresponding parts throughout the several views.

The reel is preferably made of wire and comprises a body portion 1 preferably oblong in shape, the wire being coiled substantially midway of the body portion to form the sleeve 2 which is parallel to the ends of the body portion. From three of the corners of the body portion a coiled wire arm, or twisted wire arm, 3 extends outwardly and terminates in an eye 4, and from the fourth corner a longer angular arm 5 extends outwardly and terminates in an eye 6.

A handle 7 formed of a wire loop is pro-

vided, the wire beyond the handle being twisted upon itself and passed through the sleeve 2 and terminating beyond the same in the eye 8 that prevents withdrawal of the handle from the body of the reel. The body 1 is supported and rotates upon the portion of the handle that passes through the sleeve 2 and said body may be manually rotated upon the handle to wind or unwind the line 9. The line is wound about the ends or shorter sides of the body portion and the arms 3, 5 prevent it from slipping off the body portion.

What is claimed is:

In a clothes line reel, an oblong body portion formed of a single strand of wire, a sleeve integral with said body portion formed by coiling the wire comprising the longer sides thereof, said sleeve being parallel with the ends of the body portion, arms at the corners of said body portion formed by twisting the wire upon itself and extending it obliquely outward, eyes formed at the free ends of said arms, one of said arms being substantially longer than any of the others, and a handle extending through said sleeve portion and supporting said body portion.

In testimony that I claim the foregoing as my own I have hereto affixed my signature.

CARL OSCAR SWANSON.
